ATTORNEY

UNITED STATES PATENT OFFICE.

JOHN B. ZORN, OF KANSAS CITY, MISSOURI.

ICE SHAVER AND CRACKER.

1,385,294.

Specification of Letters Patent. Patented July 19, 1921.

Application filed May 31, 1921. Serial No. 473,581.

To all whom it may concern:

Be it known that I, JOHN B. ZORN, a citizen of the United States, residing at Kansas City, in the county of Jackson and State of Missouri, have invented certain new and useful Improvements in Ice Shavers and Crackers; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a combined ice shaver and cracker and the invention is particularly designed for domestic purposes.

One of the objects of the invention is to provide a novel construction of ice shaver and cracker provided with a blade or pick which may serve for planing or shaving the ice, there being a guard or gage for the blade which will permit it to be utilized as a pick or cracker to break off the ice in larger pieces suitable for iced drinks and the like.

The device is provided with a container or receptacle to receive the shaved or cracked ice which may be subsequently released therefrom after an appropriate amount of shaved or cracked ice has been accumulated.

The preferred construction of my invention has the advantage that it can be operated by one hand, the impelling force and the pressure requisite to either shave or crack the ice being imparted to it by one hand in contra-distinction to those forms of ice shavers in which the ice is scraped by pulling the device across the surface of the ice with one hand and applying pressure with the other.

The novel construction of the invention will be apparent by reference to the following description in connection with the accompanying drawings, in which—

Figure 1 is a perspective view of an ice shaver and cracker constructed in accordance with my invention, parts being broken away to show the method of adjustably securing the gage and gate partially closing the entrance end of the receptacle.

Fig. 2 is a vertical, longitudinal, sectional

view showing the position of the gage and gate when the device is to be used as a scraper, the open position of the pivoted cover for the exit end of the device being shown in dotted lines.

Fig. 3 is a vertical, longitudinal, sectional view through the device showing the gage and gate adjusted to permit the blade to be used as a pick for cracking the ice into larger particles than when in the position shown in Fig. 2, and

Fig. 4 is a fragmentary sectional view through one side portion of the gage or gate and one side wall of the receptacle to illustrate the means for frictionally holding the gage or gate in an adjusted position.

The receptacle is shown as consisting of a floor portion 1 and two upstanding side walls 2 and 3, the forward portions of the side walls 2 and 3 being inclined downwardly as at 4 and 5. The upper and rear portion of the receptacle is closed by a pivoted cover 6 pivoted to the walls 2 and 3 at 7 and 8 and the cover 6 has a downwardly extending portion 9 which closes the rear end of the receptacle. The cover 6 is also provided with flanges 10 and 11, which overlap the free edges of the side walls 2 and 3 so as to effect an efficient closer for the top and rear end of the receptacle formed by the bottom 1, sides 2 and 3 and the cover 6.

Fastened to the floor 1 of the receptacle is a blade 12, which may consist of spring metal, preferably spring steel, anchored to the floor 1 at a point distant from the inlet end 13 by the fastening device 14. The blade lies against the floor 14 for a portion of its length and it is then curved upwardly and downwardly, as at 15, the extreme forward cutting edge 16 of the blade being slightly concave transversely, as clearly indicated in Fig. 2, to make it slightly trough-shaped, so that it can penetrate beyond the surface of the ice cake.

The blade 16 extends slightly beyond the forward end of the floor 1 and through the inlet opening 17, which is partially closed by the gage and gate 18, having downwardly extending flanges 19 and 20, which are pivoted to the side walls 2 and 3, as at 21 and 22. The rear end of the gate 18 has a rear-

- wardly extending lip 23, which underlies the cover 6 so that the joint between the cover and the gate can be sealed sufficiently to prevent ice from escaping therebetween.
- 5 The forward end of the gate is provided with a downwardly projecting lip 24 disposed toward the blade and this lip determines the effective area of the opening 17 and serves as a gage to determine the penetrability of the blade 12; that is, the position of the gage and gate determines whether the blade will shave the ice or crack it. If the parts are in the position shown in Fig. 2, the blade will shave the ice but if the guard 15 lip 24 is moved away therefrom by swinging the rear end of the gage or gate 18 downwardly, as shown in Fig. 3, then the forward end 16 of the blade 12 can penetrate the ice to a greater depth and remove larger portions in the form of cracked ice.
- The lip 24 also serves as a guard to prevent the ice from receding out of the inlet opening 17 as the device is moved back and forth during the operation thereof.
- 25 In order to hold the gage or gate in either of its adjusted positions, I have provided friction latching means, which is shown as consisting of a pressed-out boss or projection 25 on the flange 19, which is adapted to engage either of two pressed-out recessed portions or socket portions 26 and 27 on the side wall 2 so that if the boss 25 is in the socket 26, the gate or gage 18 will be in the position shown in Figs. 1 and 2 to permit the device to be used as an ice shaver, but if the boss or projection 25 is in the notch 27, then the gage or gate 18 will be in the position shown in Fig. 3 so that the larger pieces of ice can be removed from the ice cake.
- 40 The cover 6 will normally be closed so that as the ice is shaved or cracked from the ice cake and received into the receptacle formed by the bottom 1, side walls 2 and 3 and cover 6, it may accumulate until an appropriate amount has been received within the receptacle or until the receptacle is full, then the operator will swing the cover 6 to open position, as shown in dotted lines in Fig. 2 so that the contents may be discharged from 50 the rear of the receptacle.
- The proportion of the receptacle can be varied but in actual practice the device will be about the size shown in the drawings since the drawings indicate approximately 55 the actual size and the rear end will fit in the hand of the operator so that the thumb will grasp one side and the third and little fingers on the opposite side with the index and second fingers over the top; therefore,
- 60 the palm of the hand will press the device forwardly into operation and the index and second fingers, lying on the inclined portion of the gage or gate 18, will assist in retracting the device.
- 65 In actual practice the device will be tilted on end at an angle of about 45° so that the end of the blade can bite into the ice cake and inasmuch as the blade is resilient, it will spring back toward the end of the floor 1 when it is shaving or cutting the ice from 70 the cake, thus increasing the opening to permit the shaved or cracked ice to enter the receptacle. On the recovery stroke, however, the blade will spring into normal position, closing the gap between it and the end of the lip 24, thereby eliminating the liability of the ice to pass from the receptacle through the opening 17.
- What I claim and desire to secure by Letters-Patent is:
1. In a device of the class described, a receptacle having an opening at one end, a blade projecting through the open end, and a gate for closing said open end pivoted intermediate its ends to the receptacle. 80
2. In a device of the class described, a receptacle having an opening at one end, a blade projecting through the open end, and a gate for closing said open end pivoted intermediate its ends to the receptacle, said gate having a depending lip at one end and a rearwardly projecting extension at the other, underlapping the top of the receptacle. 85
3. A device of the class described comprising a receptacle having an open end, a yielding blade fastened to the floor of the receptacle and projecting through the open end, and a gate pivoted to the sides of the receptacle having a depending lip extending 95 toward the projecting end of the blade.
4. A device of the class described comprising a receptacle having an open end, a yielding blade fastened to the floor of the receptacle and projecting through the open 105 end, a gate pivoted to the sides of the receptacle having a depending lip extending toward the projecting end of the blade, the gate being capable of swinging to two positions, one of which will move the lip away 110 from the blade and the other toward the blade, and friction means for holding the gate in either position.
5. A device of the class described comprising a receptacle having a floor, upstanding side walls, a pivoted cover carried by the side walls and closing the top and rear end of the receptacle, a gate pivoted to the forward portions of the side walls and partially closing the front end of the receptacle but 115 providing a slight opening therein, and an ice shaving and cracking blade projecting through the opening. 120
6. A device of the class described comprising a receptacle consisting of a floor, upstanding sides and a top cover closing the top and rear end of said receptacle and having an opening in the forward end thereof, a blade fastened to the floor of the receptacle 125 and extending beyond the open end thereof, 130

and a pivoted gate connected to the forward portions of the side walls and having a lip movable toward and away from the blade.

7. A device of the class described comprising a receptacle having an open end, a blade carried by the receptacle, the forward end of which is upwardly and downwardly curved and concavo-convex transversely of

the receptacle, and a pivoted gage carried by the forward end of the receptacle and having a portion movable toward and away from the blade to determine the depth of the cut made by the blade. 10

In testimony whereof I affix my signature.

JOHN B. ZORN.
